BUILDING CONSTRUCTION

Charles S. Kane, Montreal, Quebec, Canada

Application August 13, 1931, Serial No. 556,793

3 Claims. (Cl. 72—15)

This invention relates to the erection of fire-proof building structures in which the structural columns, beams, floor joists and other steel framing elements are embedded in fireproofing concrete.

In the usual structure of this class, the steel framing must be made heavy and strong enough to carry all loads without the assistance of the concrete. This is required in the interests of safe practise since the bonding of the concrete to the usual design of steel framing is not consistently such as to permit the strength of the concrete component of the framing to be safely calculated as part of the required load and stress bearing capacity.

The object of the present invention is to provide an improved construction in which the steel framing is designed so that the fireproofing concrete is combined therewith to provide a truly composite metal and concrete framing which is of such a character that the concrete component may be safely relied upon to carry a certain proportion of the load which the composite framing is called upon to bear. The principal advantage of this composite construction is that it enables the metal structure of the framing to be made lighter than heretofore so that a considerable saving in steel is effected without decreasing the strength and load bearing capacity of the fire-proof framing, since the lightness of the metal component of the framing is compensated for by the load and stress bearing capacity of the concrete component.

According to this invention, the weight of the framing is primarily reduced by substituting light welded trusses of the open web or lattice type for the heavy solid beams heretofore employed to carry the floor joists. The open structure of these trusses permits the fire-proofing concrete to combine therewith to form composite metal and concrete girders of a character permitting the concrete component to be safely relied upon to carry a definite proportion of the load which the composite girder is called upon to bear. The trusses of the composite girder are preferably made continuous at the columns and are designed to withstand all construction loads imposed thereon prior to the setting of the concrete in which the trusses are embedded. The floor joists supported by the composite girder are preferably of the trussed or open web type and, in some instances, are made continuous at the girder by the use of special field joints. This type of floor joist affords a further saving in steel and when encased in concrete

provides a composite metal and concrete joist in which the concrete component may be safely relied upon to carry a definite part of the load which the joist is required to withstand. The use of open web girders and floor joists also facilitates the placement of pipes and ducts since sleeves for the passage of these pipes and ducts may be arranged to extend through the web portions of the girders and joists prior to the pouring and setting of the concrete in which these elements are embedded.

Other advantages and characteristic features of the construction afforded by the present invention will be more readily understood from the following detail description considered in connection with the accompanying drawings, in which—

Figure 1 is an isometric view of a portion of a building structure erected in accordance with this invention.

Figure 2 is a view similar to Figure 1, but showing a modified assembly.

Figures 3 to 15 inclusive are detail views illustrating various methods of joining and supporting the steel structure of the composite girders at the columns.

Figures 16 to 23 inclusive are diagrammatic views illustrating the application of the various girder supporting methods shown in detail in Figs. 3 to 15 inclusive.

Figures 24 to 27 inclusive are detail views illustrating the method of joining contiguous girder sections.

Figures 28 and 29 are detail views illustrating a method of making rolled steel girders continuous at the columns.

Figure 30 is a detail view illustrating one method of making open web beams continuous at the girders when rolled steel girders are employed.

Figure 31 is a detail view illustrating one method of making solid rolled beams continuous at the girders when rolled steel girders are employed to carry these beams.

Figures 32 and 33 are detail views illustrating a method of mounting "through" and "butt" girder trusses at the columns.

Referring to the construction shown in Figure 1, numeral 5 designates steel floor joists of the lattice or open web type comprising top and bottom chord members 5a joined together by rods, flats, angles or other structural shapes 5b forming the web structure. These joists are carried at each end by a welded trussed steel girder

75

85

110

structure 6 passing through a series of supporting columns one of which is indicated at 7.

Each girder structure 6 comprises a plurality of separately formed sections or girders having their top and bottom chords joined together in the bays between adjacent columns and at points 6a corresponding as closely as possible to the points where the minimum chord stresses are developed. In other words, the contiguous sections forming the girder 6 are joined together approximately at points which, in a continuous beam, are technically known as the points of contra flexure at which the chord stress is theoretically zero.

Considering each girder 6 to be continuous at the columns 7, the top chord is composed of two angles 8 strong enough to withstand the positive compression and negative tension due to the construction load and part of the negative tension due to superimposed load. The bottom chord is composed of two angles 9 capable of withstanding the positive tension due to total load, the negative compression due to construction load and part of the negative compression due to superimposed load. The open web of the girder is composed of diagonals 10 in the form of rods, flats, angles or other structural shapes and is designed to withstand the construction shear stresses.

In the present instance, one girder section 6 is shown passing through the central portion of the column 7 and having its top chord connected to the top chord of the contiguous girder section by a welded joint or splice 6a which is offset with respect to the joint or splice 6a connecting the bottom chords, the location of the two splices coinciding as nearly as possible with the points of minimum chord stress.

The column 7 is shown as a composite or built up split column comprising a fabricated steel core which, at a suitable stage of construction, is embedded in the concrete fireproofing 11 including the usual reinforcing bars 12 and column hooping 13. The steel core structure of the column consists principally of four vertically extending angles arranged in pairs with the angles 14 of one pair spaced a suitable distance from the angles 15 of the remaining pair. The two pairs of column angles are tied together at intervals by tie plates 16 spanning the intervening opening 17 and welded or otherwise secured to the inwardly projecting flanges of the angles. The girder section 6 which passes through the column opening 17 is fastened to the column by angles or other structural shapes 18 welded to the top and bottom chords of the girder section and to certain of the tie plates 16.

The floor joists 5 rest on the top chord of the girder 6 preferably at points where the top chord is intersected by the diagonals 10. As indicated in Figure 1, the two series of floor joists supported by each girder 6 are arranged with the ends of one series resting on the top chord of the girder in abutting relation with the ends of the opposing series. The abutting ends of the two series of floor joists are equipped with shop-welded angles 19 bolted or otherwise secured together to make the floor joists substantially continuous at the girders. These angles 19 may also be welded or otherwise secured to the top chord of the girder 6.

After erection, the steel girders 6 and floor joists 5 are encased in fireproofing concrete which combines therewith to provide a composite steel and concrete frame of such a character that the

concrete component may be safely relied upon to carry a certain proportion of the load for which the framing is designed so that the steel structure of the framing may be made lighter than has heretofore been permissible. The fireproofing concrete is poured into suitable metal forms associated with the steel columns, girders and floor joists. In the case of the floor joists the metal forms include steel floor tiles 20 in the form of inverted channel members. These floor tiles are arranged in spaced parallel relation to provide intervening valleys for the reception of the floor joists 5. The floor of each valley is formed by a channel member 21 having its side flanges 22 directed upwardly and engaging the inner surfaces of the tile flanges 23 which form the sides of the valley. These metal forms are assembled with the floor joists and tied thereto in a suitable manner (not shown) prior to the mounting of the joists in place between the girders 6.

Pairs of negative reinforcing bars appearing at 24 in Figure 1, are mounted in the floor joist forms prior to the pouring of the concrete so that the bars of each pair are embedded in the concrete enveloping the girder 6 and the adjacent ends of contiguous floor joists 5 and extend through the open web of the girder 6 so that the ends of these rods lie close to opposite sides of the bottom chords of the floor joists.

The open web structure of the floor joists 5 permits the concrete poured into the valleys between the floor tiles 20 to bond with the metal of each joist in such manner that the resulting structure is a composite concrete and metal joist in which the bond between the metal and concrete is such that the concrete component may be safely relied upon to bear a definite proportion of the load imposed on the joist. The web portions of the floor tiles 20 which bridge the spaces between adjacent floor joists serve to support the wire-mesh reinforced concrete floor slabs 25 during setting of the concrete.

Suitable metal forms (not shown) are also associated with each girder 6 so that the concrete poured around these girders takes the form of a T, the stem of which is indicated at 27 and the T-head at 28. The girder forms (not shown) may be tied to the girder 6 by stirrups 29 or in any other suitable manner. It will also be understood that the column forms, while not shown herein, are fabricated in a suitable manner to take the concrete 11 which is poured around the metal column structure after the girders 6 have been assembled therewith.

The open web design of the girder 6 permits the enveloping concrete to combine therewith to form a composite concrete and metal beam in which the stem portion 27 of the concrete serves to withstand the punching shear and part of the negative compression due to superimposed load while the T-head portion 28 of the concrete withstands positive compression due to superimposed load. Since in a composite beam of this nature the concrete component has a definite safe load and stress bearing capacity, the metal structure of the beam may be made correspondingly lighter.

The cost of fabricating the open web steel girders and floor joists is offset by the fact that the permissible use of this design in the composite construction described herein considerably reduces the total weight and quantity of steel used in the metal frame without sacrificing any of the advantages incident to the use of solid steel framing. In addition to the saving in steel and weight, the use of open web steel girders per-

- mits pipe sleeves to be placed in the forms to extend through the girders before the concrete is poured so that pipes or conduits may be subsequently passed through the composite concrete 5 and steel girders without drilling through steel or concrete as now required in connection with the use of solid steel or reinforced concrete framing. The use of open web trussed steel girders (especially when the companion angles of the top and 10 bottom chords are spaced apart to receive the diagonals of the web therebetween, as herein-after described) also eliminates the honey combing of the concrete beneath the girder flanges which commonly occurs in connection with the 15 concrete fireproofing of solid steel girders. Due to this honeycombing and to other defects in the bonding of the fireproofing concrete to solid steel girders and floor joists, it is not permissible to 20 erect a structure of this character unless the solid steel framing is made heavy and strong enough to carry all of the load independently of the concrete fireproofing. In a structure designed in accordance with the present invention, the concrete combines with the fabricated steel 25 girders and floor joists to provide a composite concrete and steel framing structure which is of such load bearing capacity that the weight of the steel structure may be lightened to an extent dependent upon the load and stress bearing capacity of the concrete component. The saving 30 in weight due to the use of welded open web girders and floor joists is also augmented by the use of the herein described composite columns consisting of steel cores embedded in concrete. 35 Referring again to Figure 1, it will be noted that suitable bridging is associated with the floor joists 5. In the present instance I have shown a straight bridging rod 30 crossing the top chords of the floor joists and clipped or otherwise connected thereto. I have also shown a V-type 40 bridging consisting of two lines of bridging wires or rods indicated at 31 and 32, each line being wrapped tightly around the top chord of one joist and then around the bottom chord of the next 45 joist, the ends of the wires being anchored in a suitable manner (not shown).
- Tie beams 33 are also provided for tying together adjacent columns 7. While the construction of these tie beams may be varied as herein-after described, the tie beams shown in Fig. 1 are of welded open web or trussed construction comprising top and bottom chords 34 connected by diagonals 35, the ends of the top and bottom chords being joined to the steel structure of the 50 columns by angles 36 welded or otherwise secured in place.
- In the modified assembly shown in Fig. 2, the composite column 7 is provided with a solid steel core 37 which is herein shown as consisting of a vertically extending H-beam, although other structural shapes may be substituted. In this case the trussed steel girder sections 38 and 39 (corresponding to the previously described girder sections 6) are welded to the flanges of the beam 37 through the medium of angles 40 or other structural shapes. Negative reinforcing anchor bars appearing at 41 are arranged to pass on opposite sides of the column beam 37 and beneath the outturned ends 42 of suitable concrete 55 reinforcing stirrups 43 embracing the girder sections 38 and 39, the bars 41 being also clipped together at intervals by suitable ties 44. The floor joists 5 appearing in this assembly are shown resting on the girder sections 38 and 39 so that the 60 ends of one series of joists overlap the ends of

the remaining series, but it will be understood that the floor joists may also be made continuous at the supporting girders as described in connection with Fig. 1.

The assembly shown in Fig. 2 also illustrates the manner in which pipe sleeves 46 are passed through the open web of the girder structure and embedded in the reinforcing or fireproofing concrete to facilitate the subsequent passage of pipes or conduits 47 through the composite girder. It will also be understood that similar sleeves may be arranged to extend through the open webs of the floor joists 5 prior to the pouring and setting of the concrete in which the joists are embedded.

Solid steel tie beams 48 are shown in Fig. 2 for connecting the steel cores 37 of adjacent columns, but it will be understood that these solid tie beams may be replaced by the welded trussed tie beams appearing in Fig. 1. The trussed tie beams appearing in Fig. 1 may likewise be replaced by the solid tie beams appearing in Fig. 2. The floor slab hybrid construction appearing at 49 in Fig. 2 and the ceiling lath construction appearing at 50 are also applicable to the floor joists of Fig. 1.

In place of the arrangement shown in Fig. 1 the girder section 6 passing through the columns 7 may be fastened to the steel core of the column as indicated in Figs. 3 and 4. In this case the bottom chord angles 9 of the girder section are 100 welded or otherwise secured to oppositely projecting flanges 16a formed integral with the upper edge of a tie plate 16b corresponding to the previously described tie plates 16. The tie beam 33 shown at the right of Fig. 3 corresponds to that 105 previously described in connection with Fig. 1 while the tie beam 48 appearing at the left of Fig. 3 corresponds to that described in connection with Fig. 2 and is welded or otherwise fastened to the column angles 14 through the medium of 110 suitable angles 52 or other structural shapes.

Instead of passing through the fabricated steel columns as shown in Fig. 1, the trussed steel girders 6 may be passed along one side of each column and supported therefrom as shown in 120 Figs. 5 to 7 inclusive. In this case tie beams 54 are passed through the column openings 17 and joined in end to end relation by plates 55 and bolts 56. At the opening 17 the tie beams are fastened to the column tie plates 16 by suitable 125 angles 57 welded or bolted in place. At each column the upper chord angles 8 of the girder 6 are mounted on the cantilever support afforded by the projecting end 54a of the tie beam passing through the column. The top chord angles 8 are 130 preferably equipped with a shop-welded saddle plate 58 adapted to be welded or otherwise secured to the tie beam end 54a. The bottom chord angles 9 of the girder are also equipped with a shop welded plate 59 adapted to be welded or otherwise anchored to one of the column tie plates 16 by an angle 60 which is welded or otherwise secured in place.

A further modification is shown in Figs. 8 to 10 inclusive, wherein the diagonals 62 of the trussed steel girder 63 are interposed between the companion angles 64 of the top chord and between the companion angles 65 of the bottom chord. The resulting spacing of the companion angles of the two chords gives a better bond with the 145 concrete when the latter is applied to the girder and tends to prevent honeycombing of the concrete beneath the girder flanges. In some instances, however, the girder shown in these last mentioned figures may be provided with a rein- 150

forcing plate 66 welded or otherwise secured to the upper surface of the top chord angles 64.

The girder section 63 passes along one side of the composite supporting column 67 which is provided with a solid steel core in the form of a structural steel beam 68. In this instance the top and bottom chords of the girder are supported from the steel column core by angles 69 or other structural shapes secured to one side of the steel core and projecting outwardly therefrom. The steel core 68 of the column may also be tied to the girder 63 by a bar 70 having its central portion welded to the column and its end portions bent around the top chord of the girder, as indicated at 71. When there is a narrow hallway between opposing columns 67 the tie beams spanning this hallway may consist of a T section 72 having its ends supported by the upper angles 69 which, as previously described, are employed for fastening the top chord of the girder to the steel column core.

Figs. 11 and 12 illustrate one method of passing a trussed steel girder through a column having a solid steel core. In this instance the steel core is composed of superimposed sections 75 and 76 in the form of H-beams fastened together by side plates 77 bolted or welded thereto. The web 75a of the lower section 75 is provided at its upper end with a V-shaped notch 78 and the upper chord 79a of the girder section 79 is passed through this notch, as shown, so that the top surface of the chord is practically flush with the upper end of the column section 75. The lower chord 79b of the girder section is split to provide a gap accommodating therein the web 75a of the column section 75 as shown to advantage in Fig. 12, wherein it will be noted that the ends of the chord lying at opposite sides of the gap are joined to the web 75a by welded or bolted angles 80 and plates 81. The upper chord 79a of the girder is shown as secured to the upper steel column section 76 by a welded angle 82. In erecting the assembly shown in Figs. 11 and 12 it will, of course, be understood that the girder is assembled as described with the lower steel column section 75 prior to erection of the upper steel column section 76.

Fig. 13 illustrates a slight modification of the assembly appearing in Figs. 11 and 12. According to this modification the girder is arranged with the vertical flanges 84 of the top chord passing through a slot 85 in the web 86 of the lower steel column section 87. In this instance the horizontal flanges 88 of the top girder chord rest flatly on the upper end of the web 86 between suitable filler plates 89 on which the lower end 55 of the upper column section 90 is supported.

Figs. 14 and 15 illustrate one method of making contiguous girder sections continuous at the composite column when the latter is provided with a solid steel core. In this instance the bottom chord angles 94 of the two girder sections are anchored to opposite sides of the web 95 of the steel core 96 by means of header plates 97. These header plates are preferably shop welded to the chord angles and fastened to the web 95 by welding or bolting. The top chord angles 98 of the two girder sections here referred to are shown as terminating short of the web 95 and connected together by welding to opposite ends of a tension member 99 arranged to pass through a slot 100 formed in the web 95. The tension member 99 is preferably arranged to join the top chord of the two girder sections together at points positioned at or near the points of contraflexure. Where it 75 passes through the web 95 the tension member is

preferably anchored to the web by one or more angles 101 arranged as shown and welded or otherwise fastened in place. The method of joining the girder sections as illustrated in Figs. 14 and 15 may also be used in connection with columns having a fabricated steel core of the type shown in Fig. 1. In the latter instance the bottom chord angles 94 would be suitably secured to one of the column tie plates 16 while the tension member 99 would pass through the column opening 17 and be secured to another one of the column tie plates 16.

With respect to the various girder supporting arrangements shown in Figs. 3 to 13 inclusive, it will be understood that in each instance the girder section passing through or by the steel core of the column has its top and bottom chords joined to corresponding chords of contiguous girder sections at points between the columns corresponding as nearly as practicable to the points of contraflexure or minimum chord stress. This will be readily understood from the following reference to Figs. 16 to 23 inclusive.

The girder supporting arrangement illustrated in detail in Figs. 3 and 4 is shown diagrammatically in Figs. 16 and 17, in which A indicates the steel column core, B the girders, and C the joining of contiguous girder sections at points between the columns corresponding to the points of minimum chord stress.

The by-passing of the steel column cores by the girders in accordance with the arrangements shown in detail in Figs. 5 to 10 inclusive is illustrated diagrammatically in Figs. 18 and 19, in which D designates the steel column cores, E the girder sections passing along the sides of the steel column cores, and F the joining of the girder sections at points between the column cores corresponding to the points of minimum chord stress.

The passing of the girder sections through columns equipped with solid steel cores as shown in detail in Figs. 11 to 13 inclusive is illustrated diagrammatically in Figs. 20 and 21, in which G designates the steel column cores, H the girder sections, I the joining of contiguous girder sections between the columns at points corresponding to the points of minimum chord stress, and J the joining of the column web with the separated bottom chord members of the girder section passing through the column.

The arrangement shown in detail in Figs. 14 and 15 is illustrated diagrammatically in Figs. 22 and 23 in which K indicates the steel column cores; L the contiguous girder sections; M the joints between the column cores and the bottom chord angles of the girder sections and N the tension members passing through the column cores and joined to the top chords of the girder sections at points O representing the points of minimum chord stress.

Figs. 25 to 27 inclusive illustrate a method of joining contiguous girder sections which may be utilized as an alternative to the arrangement shown in Fig. 1. In this instance the top chord angle 105 of each girder section projects beyond its companion angle 106 and overlaps the projecting angle 105 of the contiguous girder section. The end of the angle 105 of each girder section is thereby positioned close to the end of the angle 106 of the contiguous girder section and the opposing ends of these angles are joined by welding to a joint plate 107. In like manner the lower chord angle 108 of each girder section is projected beyond the companion angle 109 and

is joined to the angle 109 of the contiguous section by a welded plate 110. The web of the girder is formed by diagonal angles 111 welded to the vertical legs of the top and bottom chord angles 5 and the shear introduced between the chord angles is provided for by making the vertical leg of one top and one bottom chord angle longer than the vertical leg of the companion angle to provide additional welding space for developing 10 this shear.

Figs. 28 and 29 illustrate a method of making contiguous girder sections continuous at the solid steel cores of the columns when rolled solid steel girders are substituted for the previously 15 described trussed or welded open web girders, such substitutions being sometimes necessary or desirable in certain positions of a structure erected in accordance with this invention. In these figures the steel column core comprises superimposed sections 113 and 114 joined together by bolted or welded side plates 115. The solid rolled girder sections are indicated at 116 and 117. The lower opposing end portions of these girder sections carry shop welded header plates 118 bolted 20 or otherwise secured to opposite sides of the web portion 119 of the lower column section 114. At their upper surfaces the opposing ends of the girder sections are welded to the extremities of a tension member 120 passing between filler plates 25 121 separating the adjacent ends of the column sections 113 and 114. The tension member 120 serves to join the girder sections 116 and 117 at points closely approximating the points of contraflexure and serves to induce continuity of the 30 girder sections at the columns.

When the columns are spanned by rolled solid girders these girders may be employed to carry welded open web beams as shown in Fig. 30 or rolled solid beams as shown in Fig. 31.

40 In the construction shown in Fig. 30, the rolled girder is indicated at 125 and serves to support the adjacent ends of contiguous open web beams 126 and 127. The bottom chords of the beams are joined to the web of the girder by header plates 128. The top chords of the beams stop short of the girder and are made continuous by joining to the ends of a tension member 129 which passes over the top of the girder and joins the top of the beams at points corresponding approximately to the points of minimum chord stress.

45 In the construction shown in Fig. 31 the adjacent ends of the rolled beams 130 and 131 have their lower portions joined to the web of the rolled girder 132 by suitable header plates 133. The upper end portions of the beams 130 and 131 are made substantially continuous by joining to the ends of a tension member 134 passing across the top of the girder and joining the beams at or 50 near the points of minimum chord stress.

55 Figs. 32 and 33 show further modifications dealing with the anchorage of both "butt" and "through" trusses at the columns. The steel column cores illustrated in these figures is of the fabricated construction shown in Fig. 1. The "through" truss indicated at 136 passes through the column opening 17 and is anchored to certain of the column tie plates 16 by the angles 137 and the plate 138. The top chord angles of the truss 60 136 are also preferably reinforced by tension rods 139 welded thereto and also extending through the column opening 17. The "butt" trusses indicated at 140 and 141 have their bottom chords fastened to the column angles 14 and 15 by angle plates or other structural shapes 142. The top

chord angles of the "butt" trusses 140 and 141 are joined at points corresponding to the points of minimum chord stress by tension rods 143 welded thereto and passing through suitable openings formed in the column angles 14 and 15. The top chord angles of the "butt" trusses 140 and 141 are also joined directly to the column flanges 14 and 15 by suitable angles 143a.

65 While Figs. 32 and 33 show the "through" truss 136 and the "butt" trusses 140 and 141 joined to a split column, it will be understood that the same construction could be used in connection with a solid column by providing the column with suitable slots or openings for the passage of the tension rods 139 and 143.

70 Having thus described my invention, what I claim is:

1. A composite metal and concrete building structure including composite columns comprising relatively light self-sustaining lattice type steel column cores embedded in concrete, composite girders supported by said columns, each girder being arranged to span the spaces between a row of columns and consisting of contiguous open web steel trusses embedded in concrete 75 continuous with the concrete components of the columns, the ends of the girder trusses being secured to and supported by the steel column cores and composite floor joists supported between adjacent girders each floor joist comprising a welded open web truss embedded in concrete continuous with the concrete components of the girders, the ends of the steel trusses of the floor joists being supported on and secured to the top chords of the steel trusses of the girders, and the contiguous steel trusses of each girder being joined together in end to end relation to form a continuous beam passing through openings in the steel column cores, the joints between the component girders of said beam being located at 80 points approximating the points of contraflexure or minimum chord stress.

2. A composite metal and concrete building structure including composite columns comprising steel column cores embedded in concrete, composite girders supported by said columns, each girder being arranged to span the spaces between a row of columns and consisting of contiguous open web steel trusses embedded in concrete, the bottom chords of the contiguous trusses of each 85 girder being anchored to the steel column cores by field joints and the top chords of said trusses terminating short of the steel column cores and being welded to the extremities of a tension member passing through the columns, said tension member joining the top chords of the girders at 90 points approximating the points of contraflexure or minimum chord stress and serving to assist in taking care of negative tension.

3. A fireproof building structure comprising a 95 light, rigid and self-sustaining steel frame comprising self-sustaining lattice type steel column cores, a built-up girder spanning the spaces between each series of columns and consisting of contiguous open-web or lattice type steel trusses having the top and bottom chords joined together in end to end relation to form a continuous beam extending through apertures of the steel column cores, the joints between the top and bottom chords of the contiguous girder sections being located at points approximating the points of contraflexure or minimum chord stress, a series of floor joists supported between parallel girders, each floor joist comprising an open-web steel truss, the steel trusses of contiguous floor joists 100

being joined together at the girders in end to end relation, the aforesaid elements of the steel framing being embedded in concrete so that the concrete component of the steel column cores is made continuous with the concrete component of the girders and the steel floor joists to provide a

composite metal and concrete structure in which the concrete is bonded with the open-work elements of the steel frame in such a way as to safely carry a considerable proportion of the total load.
